UNITED STATES PATENT OFFICE

LESLIE A. KEMPTON, OF BRIDGEPORT, CONNECTICUT, ASSIGNOR TO GENERAL ELECTRIC COMPANY, A CORPORATION OF NEW YORK

SWITCH BLADE

Application filed October 30, 1929. Serial No. 403,597.

The present invention relates to blades for snap switches and especially to switches intended for controlling the circuits of electric heating devices, as for example electric 5 ranges. Such switch blades have to carry relatively large amounts of current and are frequently operated. Although means are provided for actuating the movable member or blade with a snap action, it is found in 10 practice that arcing takes place when the circuit is opened which causes burning or pitting of the surfaces thereof. When the surfaces become roughened in this manner the contact between the moving and stationary 15 parts is impaired, which in turn causes local heating of the parts which is objectionable as will readily be appreciated. In order to improve the operation it is the standard practice to coat the contacting surfaces with some 20 kind of grease or heavy oil which while it makes the parts move easily has the effect, especially where an excess of grease is used, of increasing the trouble incident to arcing.

My invention has for its object to improve 25 the construction of switch members or blades or both by providing embossments thereon to the end that the arcing or burning is confined to portions of the surfaces or parts of the members or blades other than at the embossments through which the current flows when 30 the switch is closed.

For a consideration of what I believe to be novel and my invention, attention is directed to the accompanying description and 35 the claims appended thereto.

In the accompanying drawing, which is illustrative of my invention, Fig. 1 is a plan view of a rotatable switch blade, Fig. 2 is an edge view showing how the parts are arranged in a switch, Fig. 3 is an end view of 40 one of the blade arms, and Fig. 4 is a sectional view on an enlarged scale of a pair of moving blades and a stationary contact.

In order to simplify the description of my 45 invention, the details of the switch operating mechanism as well as some of the other parts have been omitted. It is to be understood, however, that in this particular any suitable operating mechanism may be employed and 50 any suitable arrangement of the stationary

contacts and movable blades. For example, the structure shown in my Patent 1,670,073 granted May 15, 1928 may be used.

5 indicates a four arm switch blade or spring contact brush, two of said arms being longer than the others so as to engage a different set of stationary contacts, one pair of arms extending at right angles to the other pair. They are made of good spring material, such as phosphor bronze or equivalent metal. They are assembled in the switch in pairs as shown in Fig. 2, and as many pairs may be provided as are necessary for controlling the circuits of the heating or other devices associated with the switch. 60 The blades or brushes are so made and assembled as to be biased toward each other so as to make good contact with the stationary contacts. 6 indicates stationary contacts which are bridged by the blades to close the circuit 65 between them.

Instead of making the contact surfaces at the ends perfectly flat and smooth and flush with the body of the blade as is the standard practice, each is provided with a shallow 70 embossment 7 which rises slightly above the metal forming the other part. The embossments are formed by suitable dies, and their surface area should be great enough to carry the current without appreciable local heating. The amount that each embossment is raised will depend chiefly upon the thickness of the stationary contact and on the shape or curvature of the edges of the blades. For 75 example, in switches designed for 225 volts and 36 amperes, as shown, the embossment may be raised by an amount of the order of to one-quarter of the thickness of the blade. The object is to raise it as little as possible and yet provide a surface which will 80 remain smooth and free from burning due to arcing when the circuit is broken. The end portions of each blade arm are bent or curved away from the plane of the blade to a lower level as indicated at 8 starting at or 85 near the base of the embossment so that all danger of the parts jamming when the blade is moved is obviated, and to cause whatever arc is formed to be beyond the embossment. 90 The amount that the ends are bent or curved 100

will depend chiefly upon the thickness of the stationary contacts. The point is they should afford an easy entrance for the contact between the blades as well as form arcing surfaces below the level of the embossment.

The entering edges of the stationary contacts are beveled or sharpened as shown at 9 in Fig. 4. As the pair of moving blades is rotated by a suitable means (not shown) to

- 10 interrupt the circuit, the embossments pass out of engagement with the stationary contact and due to the spring of the blade arms they move toward each other, still grasping the contact between them but in regions beyond the embossments. This has the effect of causing the arcing to take place not at or on the embossments but in a region or regions outside thereof, for example as at 10 and 11, the arc following the metal outward
- 15 from the embossments until broken by relative movements of the stationary and moving parts. To state the matter in other words, the embossments ride on the stationary contact, then move toward each other while other parts of the blade maintain the electric circuit and the arc is finally broken at the level or region below and beyond the embossments.
- 20 As a preferred arrangement, I have shown a pair of blades engaging opposite sides of the same stationary contact but where the currents to be carried are small a single blade may be employed, having of course, the embossment arranged in the manner described. In this case the arc will be obliged to follow
- 25 one path instead of two.

Tests made with switches embodying my improved blade show substantial improvement over the prior smooth or non-embossment type in the absence of roughening, pitting and local heating. For example, switches fitted with my improvement have been given a rotary test of 12,000 cycles without any trouble from flashing or burning, and the embossments remained smooth and clean, such roughening and pitting as took place being wholly outside the embossments. In the particular test referred to, the voltage was 255 and the current 36 amperes. In one test the switch was placed in circuit with a high heat coil of a range on a 112 volt circuit with a current of 48 amperes, and after 144 hours of operation had a temperature of 125° F., with a room temperature of 92° F., or a rise of only 33° F. over room temperature, which is substantially less than is normally the case. Due to the fact that the contacting surfaces remain smooth, the local heating of the switch at the contacts as indicated above is small, and the life of the switch is thereby increased.

What I claim as new and desire to secure by Letters Patent of the United States is:

1. In combination, a pair of sheet metal switch blades, each of which has a shallow embossment pressed therefrom to form a flat

contact surface of considerable area which rises above the level of the surrounding part of the blade, said embossments facing each other, with a stationary contact adapted to be engaged on opposite sides successively by the embossments and the surrounding parts of the blades as the blades move out of engagement with the stationary contact.

2. In combination, a rigid contact and a spring contact brush adapted to engage said rigid contact and having an embossment forming a contact surface and an adjacent surface adapted to engage the rigid contact as the contact brush is separated from said rigid contact to open an electric circuit, and provide an arcing surface for said contact brush.

3. In combination, a rigid contact and spring contact brushes adapted to engage said rigid contact and having embossments forming contact surfaces and surfaces adjacent said contact surfaces adapted to engage the rigid contact as the contact brushes separate from said rigid contact to open an electric circuit, and provide arcing surfaces for said contact brushes.

4. In combination, a rigid contact and two spring contact brushes adapted to engage said rigid contact and having embossments forming contact surfaces engaging opposite sides of said rigid contact and surfaces adjacent said contact surfaces adapted to engage the rigid contact as the contact brushes separate from said rigid contact to open an electric circuit, and provide arcing surfaces for said contact brushes.

5. A switch member comprising two spring contact brushes having embossments forming contact surfaces on the inner sides of the brushes and surfaces adjacent to the embossments forming arcing surfaces which are adapted to engage a contact after the embossments have passed out of engagement with the contact whereby the arcing of the contact brushes is limited to an area which is not in normal engagement with the contact when an electric current is passing therethrough.

6. A switch member comprising two spring contact brushes biased toward each other and having shallow embossments on the inner side of the contact brushes forming flat contact surfaces raised above the adjacent surface of the contact brush whereby the surfaces adjacent to the embossments engage a contact as the electric circuit is opened through the switch member to prevent the pitting and arcing of the contact surfaces.

In witness whereof, I have hereunto set my hand this 26th day of October, 1929.

LESLIE A. KEMPTON.
